UNITED STATES PATENT OFFICE.

FRANK L. BARNES AND JOHN McGOEY, OF NEW YORK, N. Y.

UNION SUIT.

1,074,309.

Specification of Letters Patent. Patented Sept. 20, 1913.

Application filed March 12, 1912. Serial No. 653,206.

To all whom it may concern:

Be it known that we, FRANK L. BARNES and JOHN McGOEY, citizens of the United States, residing at New York, county of New York, and State of New York, have invented certain new and useful Improvements in Union Suits, fully described and represented in the following specification and the accompanying drawings, forming a part of the same.

This invention relates to that class of underwear known as union suits, and the invention is especially intended for knitted underwear of this class, although applicable also to union suits of other material including those made wholly or partly of non-elastic material.

The especial object of the invention is to provide an improved union suit of that class in which the posterior opening does not extend through the crotch to the front opening, but the crotch is permanently closed and the posterior opening is opened and closed by a side flap, and particularly to provide a garment having a freer and better opening of the seat flap and securing greater comfort and a better fit.

In the accompanying drawings forming a part of this specification a union suit embodying all the features of the invention in its preferred form is shown, and this construction will now be described and the features forming the invention then specifically pointed out in the claims.

In the drawings:—Figure 1 is a perspective side view of the union suit on the wearer in a standing position; Fig. 2 is a similar view showing the wearer in front view, seated; Fig. 3 is a rear elevation of the suit, and Fig. 4 is a plan view looking at the crotch laid out flat.

Referring to the drawings, A is the main body of the union suit having the front opening 1 extending down to, or nearly to, the crotch, and shown as buttoned, as usual, and having the posterior opening 2 extending upward from a point at or near the crotch to a point in the back such as to give the desired freedom of opening and closing the posterior opening 2 by the seat flap *a*, shown as secured by the button *b*. The outer flap *a* is formed by a separate piece extending down to the crotch and into the leg, as shown in Figs. 3 and 4, and inside this flap *a* is the inner flap *b* also shown as

formed of a separate piece extending from the upper end of the posterior opening down to the crotch and into the leg, as shown partly in dotted lines in Figs. 3 and 4. The crotch is closed between the openings 1, 2 by a gusset *c* extending across the crotch and down into each leg and preferably formed of elastic material such as knit material with its wales extending transversely to the gusset so that the gusset is elastic longitudinally, the length of the gusset thus allowing a considerable stretch of the garment longitudinally of the gusset. The gusset *c* is a closed gusset, that is, its edges are secured entirely about the gusset, the preferred construction being that shown in which the gusset is seamed on the rear side to the flaps *a*, *b* of the garment, and on the front side to the opposite sides of the opening 1 and the openings 1, 2 terminate at their ends at the gusset.

The invention provides a very comfortable and well-fitting garment in which a very satisfactory operation of the flap in opening and closing the seat portion is secured with the single closing flap extending downward to a point on or near the central line of the garment and with the permanently closed crotch. It will be understood, however, that while the posterior opening and closing flap preferably extend downward to a point at or near the middle line of the garment, as shown, and such a construction forms a specific part of the invention, the elongated closed gusset forming a permanently closed crotch may be used with posterior openings and flaps otherwise formed, and the invention, broadly considered, is not limited to the particular construction or arrangement of seat openings and seat flap shown.

What we claim is:

1. A union suit having a narrow elongated gusset extending across the crotch and downward on the inside of the legs and forming a permanent closure of the crotch, said gusset being of greater elasticity longitudinally of the gusset than transversely of the gusset, and the suit having a posterior opening extending upward from the gusset and overlapping seat flaps having their bottom edges secured to the gusset and free on one side for opening and closing said posterior opening.
2. A union suit having a narrow elongated

gated gusset extending across the crotch and downward on the inside of the legs and forming a permanent closure of the crotch, said gusset being of greater elasticity longitudinally of the gusset than transversely of the gusset, and the suit having a posterior opening extending upward from the gusset at a point substantially at the central line of the garment and overlapping seat flaps having their bottom edges secured to

the gusset and free on one side for opening and closing said posterior opening.

In testimony whereof, we have hereunto set our hands in the presence of two subscribing witnesses.

FRANK L. BARNES.
JOHN McGOEY.
